UNITED STATES PATENT OFFICE.

JOSEPH D. TROMBLEY, OF CHEBOYGAN, MICHIGAN, ASSIGNOR OF ONE-HALF TO JOSEPH KESSELER, OF CHEBOYGAN, MICHIGAN.

MUSIC-LEAF TURNER.

SPECIFICATION forming part of Letters Patent No. 788,740, dated May 2, 1905.

Application filed March 1, 1905. Serial No. 247,955.

To all whom it may concern:

Be it known that I, JOSEPH D. TROMBLEY, a citizen of the United States, residing at Cheboygan, in the county of Cheboygan and State of Michigan, have invented a new and useful Music-Leaf Turner, of which the following is a specification.

This invention relates to music-leaf turners, and has for its object to provide certain new and useful improvements in devices of this class to particularly adapt the same for application to upright pianos and to arrange the same for effective actuation by the knee of the player without obstructing the keyboard in any manner whatsoever. It is furthermore designed to provide for attaching the device to a piano without altering or changing the latter in any manner whatsoever beyond the application thereto of such bearings and brackets as are necessary for the support of the actuating parts of the device.

Another object of the invention is to effect convenient engagement of the leaf-turning members with the leaves of the music and to insure the turning of only one sheet at a time.

With these and other objects in view the present invention consists in the combination and arrangement of parts, as will be herein-after more fully described, shown in the accompanying drawings, and particularly pointed out in the appended claims.

In the accompanying drawings, Figure 1 is a front elevation of an upright piano having the leaf-turner of the present invention applied thereto. Fig. 2 is an enlarged detail view of the music-leaf turner. Fig. 3 is an enlarged detail horizontal sectional view of the device. Fig. 4 is an enlarged vertical sectional view taken through the rotary shifting member for moving the leaf-engaging members. Fig. 5 is a detail perspective view of the rotary shifting member. Fig. 6 is a detail perspective view of the cam with which the shifting member cooperates. Fig. 7 is an enlarged detail cross-sectional view on the line 7-7 of Fig. 2.

Like characters of reference designate corresponding parts in each and every figure of the drawings.

The present device includes a music-rack 1 in the nature of an oblong open frame provided at its lower edge with a leaf-supporting ledge or flange 2, there being suitable supports or feet 3 at opposite ends of the rack for supporting the device upon the usual music-rail 4 of any ordinary form of upright piano, (shown at 5 in Fig. 1 of the drawings.) At the middle of the ledge or flange 2 the latter is cut away, as at 6, and there is a substantially horizontal bar 7 hung beneath this cut-away portion by means of hangers 8, secured to the under side of the flange or ledge 2 at opposite ends of the cut-away portion 6.

An upright spindle 9 has its lower end stepped in the cross-bar 7, which forms a step 65 bearing or bracket for the spindle, the upper portion of the latter being let into a longitudinal groove or seat 10, formed in the music-rack. Upon the spindle 9 and in the open space between the bar 7 and the ledge or flange 2 there is a gear 11, which is provided upon its upper face with an upstanding trip projection 12, having an inclined or beveled top end 13, said projection working in an arcuate upright slot 14, formed concentrically in a cam 75 15, which has an opening 16 disposed concentrically with respect to the slot 14 and through which the spindle 9 extends. At the rear of the cam 15 there is an extended attaching portion 17, which is suitably secured to the under 80 side of the music-rack.

Each of the leaf-turning members consists of an upstanding finger, there being three such fingers shown in the accompanying drawings and designated A, B, and C, each finger terminating at its lower end in a laterally-directed arm 18, having a terminal eye or bearing 19 rotatably embracing the spindle 9 below the gear 11, there being another arm, 20, projected laterally from the finger above the lower arm 90 and across the top of the cam, with the outer end of this arm terminating in an eye or bearing 21, loosely embracing the spindle 9, whereby the two arms and the finger carried thereby are capable of being swung around the 95 spindle 9 as a center. The successive upper arms 20 work across the cam in frictional engagement therewith and when swung to the

right-hand side of the device lie one upon the other, as best indicated in Fig. 4, with the lowermost arm lying upon the top of the cam and the other arms decreasing in length upwardly therefrom. The lowermost arm is in the path of the trip projection 12, carried by the gear 11, when moving outwardly through the arcuate slot 14, whereby the lowermost arm and its finger A will be swung from the right-hand side of the device to the left-hand side thereof. During the swinging of the finger A from the right to the left the arm 20 gravitates upon the cam until it reaches its left-hand limit by striking against the rack, and when it reaches its left-hand limit its bearing 21 is received in the opening 16, thereby letting the next upper arm 20 down upon the cam. When the gear 11 is rotated in a backward direction to its original position, the beveled end of the trip projection 12 wipes beneath the lowermost arm 20 and passes to the rear thereof in position for engagement with the rear side of the lowermost arm 20 when the trip projection is again moved forwardly, whereby the several music-leaf-engaging members may be readily swung from right to left.

For convenience in rotatably shifting the gear 11 to actuate the leaf-engaging members there is a gear 22 in mesh with the gear 11 and journaled upon an upright frame-bar 23 at the back of the music-rack, there being a drive-shaft 24 journaled in the bar 23 and one of the feet 3 in rear of the music-rack. Upon the shaft 24 is a gear 25, in mesh with the gear 22, and another gear, 26, is carried by the outer end of the shaft at the outer side of the foot 3. An upright shaft 27 is mounted in upper and lower bearings 28 and 29, secured upon the adjacent end of the piano-case, the upper end of the shaft being provided with a gear 30, in mesh with the gear 26. The bracket 28 has an overhanging shield 31, which guards and houses the gears 26 and 30, with the upper end of the shield extended downwardly in rear of the gear 26 and pierced by the shaft 24 to form a bearing-bracket 32 for the extremity of said shaft. Upon the lower end of the shaft 27 there is a pinion 33, which is in mesh with an endwise-movable rack 34 upon the adjacent end of a horizontal endwise-movable rod 35, mounted to work through bearings 36 and 37, secured upon the under side of the keyboard of the piano-case and provided with a hinge-joint 38 in that end portion of the rod which projects beyond the bearing 36. There is a pin or shoulder 39, carried by the rod 35 at the left-hand side of the bearing 36, and a helical spring 40, embracing the rod and engaging against the shoulder and the bearing 36 to yieldably maintain the rod 35 at its left-hand limit. A horizontally-movable lever 41 is hinged to the under side of the keyboard and connected to 65 the rod 35 at a suitable distance to the right

of the middle of the piano and in position for movement to the right by pressure of the right knee of the player.

In using the present device the music is placed upon the music-rack in the usual manner and the leaf-turning members A, B, and C are engaged back of the respective leaves to be turned. By pressing to the right upon the knee-lever 41 the rod 35 will be shifted to the right, and through the medium of the rack 34 and the pinion 33 the shaft 37 will be rotated in the direction of the arrow thereon in Fig. 2, thereby turning the shaft 24 in a direction to rotatably shift the gear 11 from the right to the left, the trip projection 12 of course engaging the lowermost arm 20 and swinging the same and the finger A around to the left, whereby the leaf in front of the finger A will also be turned to the left. It will here be noted that the swinging movement of each leaf-turning member from the right to the left is limited by reason of its upper arm 20 engaging the upright transversely-disposed shoulder 42 at the left-hand low side of the cam. Upon removing the pressure of the knee from the lever 41 the spring 40 will automatically return the rod 35 to its original position, thereby rotating the member 11 back to its original position in readiness to turn the next leaf-engaging finger, and so on throughout the series of fingers.

Having thus described the invention, what is claimed is—

1. A music-leaf turner comprising a music-rack, a cam carried by the rack and provided with an inclined upper face and an arcuate slot intersecting its upper face, a series of leaf-turning members mounted to rotate concentrically with respect to the slot and traveling over the inclined upper face of the cam, a trip member working in and projected through the slot for successive engagement with the leaf-turning members, and means for working the projection back and forth in the slot.

2. A music-leaf turner comprising a rack, a cam carried by the rack and provided with an inclined upper face which is intersected by an arcuate slot, a spindle piercing the cam concentrically with respect to the slot, a trip working in the slot and projected above the top of the cam, means for working the projection in the slot, and a series of leaf-turning members having lateral arms mounted to swing upon the spindle and traveling in frictional engagement across the inclined top of the cam in the path of the trip projection.

3. A music-leaf turner comprising a rack, a cam carried by the rack and projected in front thereof with its upper face inclined downwardly from right to left and intersected by an arcuate slot, a spindle rising from the cam concentrically with respect to the slot, a trip projection extending upwardly through the slot and working back and forth therein

with its upper end rising above the top of the cam, and a series of leaf-turning members, each leaf-turning member having a lower arm rotatably mounted upon the spindle below the cam and also provided with an upper arm rotatably mounted upon the spindle above the cam and working in frictional engagement upon the top thereof in the path of the trip projection.

10 4. A music-leaf turner comprising a cam having an inclined upper face, a spindle rising from the cam, a trip member traveling concentrically around the spindle, a series of leaf-turning members mounted to rotate upon the spindle and loose thereon to gravitate upon the inclined face of the cam, said members being supported one upon another when turned to the right, and means to work the trip member back and forth to successively swing the 20 leaf-turning members from the right to the left.

5 5. A music-leaf turner comprising a cam having its upper face inclined downwardly from the right to the left and provided with an arcuate slot intersecting the top and bottom thereof, a spindle piercing the cam and projecting at the top and bottom thereof concentrically with the slot, a series of leaf-turning members, each member having upper and 30 lower arms mounted to rotate upon the spindle and located above and below the cam, the upper arm working in frictional engagement across the top of the cam, the series of upper arms being supported one upon another when turned to the right, and a trip member working in the slot and projected above the top of the cam for engagement with the lowermost upper arm at the right-hand side of the cam to swing the leaf-turning member from the 40 right to the left.

6. A music-leaf turner comprising a support, a leaf-turning member mounted to rotate upon the support, a gear to rotate the member, a substantially horizontal drive-shaft, a connection between the shaft and the gear, an upright power-shaft geared to the drive-shaft, a pinion upon the upright shaft, a substantially 45

horizontal endwise-movable rack-bar engaging the pinion, and a controlling-lever connected to the rack-bar.

50

7. The combination with an upright piano, of a swinging leaf-turning member mounted thereon, a substantially horizontal drive-shaft geared to the leaf-turning member, an upright power-shaft mounted upon one end of the piano-case and geared to the drive-shaft, and knee-controlled means mounted upon the under side of the keyboard of a piano and connected to the upright power-shaft for rotating the same.

60

8. In a music-leaf turner, the combination of a music-rack, a cam carried by the rack and projected in front thereof with its upper face inclined downwardly from right to left and provided with an arcuate slot intersecting the top and bottom of the cam and an opening piercing the cam concentrically with respect to the slot, there being an upstanding shoulder at the low left-hand side of the cam, a spindle projecting through the opening above and below the cam, a gear mounted upon the spindle beneath the cam and provided with an upstanding trip projection working in the slot and projected above the top of the cam, a series of upstanding leaf-turning members having upper and lower transverse arms mounted to turn upon the spindle above and below the cam, the upper arms working in frictional engagement across the inclined top of the cam and supported one upon another when located at the right-hand side of the cam, a drive-shaft geared to the gear, an upright power-shaft geared to the drive-shaft, a pinion upon the power-shaft, an endwise-movable rack-bar for engagement with the pinion, and a knee-actuated lever connected to the rack-bar.

65

In testimony that I claim the foregoing as my own I have hereto affixed my signature in the presence of two witnesses.

JOSEPH D. TROMBLEY.
